ATTORNEY:

UNITED STATES PATENT OFFICE.

GEORGE W. COPE, OF DETROIT, MICHIGAN, ASSIGNOR TO THE FOSTER STOVE COMPANY, OF IRONTON, OHIO.

DESIGN FOR A STOVE.

SPECIFICATION forming part of Design No. 22,430, dated May 9, 1893.

Application filed March 17, 1893. Serial No. 466,722. Term of patent 7 years.

To all whom it may concern:

Be it known that I, GEORGE W. COPE, a citizen of the United States, residing at Detroit, in the county of Wayne and State of Michigan, have invented and produced a new and original Design for Stoves; and I do declare the following to be a full, clear, and exact description of the same, reference being had to the accompanying drawing, forming a part thereof.

My invention relates to a new and original design for cooking stoves, the leading features of which consist in the configuration or shape of the oven and grate doors, and the character and style of the ornamentation.

The accompanying drawing represents a perspective view of a cooking stove showing my design.

The oven door has a straight bottom and top side or edge, a vertical rear end or edge and a beveled or inclined front end or edge, and the grate door is similarly formed except that the rear end or edge is beveled or inclined instead of the front end. The plate below the grate door is also beveled in line with the bevel of the grate door.

The style or character of the ornamentation

consists in a series of volute ornamental scrolls. As seen in the drawing the scrolls at the lower front end of the oven door, radiate from a common center forming an ornamental rosette. At the opposite diagonal end, the scrolls are arranged somewhat different yet presenting the same characteristics and harmonizing therewith. On the grate door I provide volute scrolls and locate them diagonally opposite.

A stove with my design applied thereto will be very attractive and present a pleasing appearance to the eye.

I claim—

1. In the design for a stove, the door comprising the straight top and bottom sides, the straight vertical end, the beveled opposite end and the ornamental scrolls in relief, as shown and described.

2. The design for a stove as herein shown and described.

In testimony whereof I affix my signature in presence of two witnesses.

GEORGE W. COPE.
